DESIGN FOR A TOY BEAR OR SIMILAR ARTICLE

Zinaida Harpignies, New York, N. Y.

Application February 16, 1944, Serial No. 112,603

Term of patent 3½ years

(Cl. D34—2)

To all whom it may concern:

Be it known that I, Zinaida Harpignies, a citizen of Belgium, residing at 10 West 65th St., New York city, in the county of New York and State of New York, have invented a new, original, and ornamental Design for a Toy Bear or Similar Article, of which the following is a specification, reference being had to the accompanying drawing, forming part thereof.

In the drawing

Fig. 1 is a front view of a toy bear or similar article showing my new design;

Fig. 2 is a side view of the toy bear shown in Fig. 1; and

Fig. 3 is a back view of the toy bear shown in Fig. 1.

I claim:

The ornamental design for a toy bear or similar article, as shown.
